US00D805112S

(12) **United States Design Patent** (10) **Patent No.:** **US D805,112 S**
(45) **Date of Patent:** **** Dec. 12, 2017**

(54) **TIP FOR A GROUND ENGAGING MACHINE IMPLEMENT**

3,019,537 A 2/1962 Stephenson
3,079,710 A 3/1963 Larsen et al.
3,312,004 A 4/1967 Johnson

(71) Applicant: **Caterpillar Inc.**, Peoria, IL (US)

(72) Inventors: **Douglas Serrurier**, Morton, IL (US);
Jason Jura, Peoria, IL (US); **Eric Sinn**,
East Peoria, IL (US); **Mihai Mircea**
Balan, Dunlap, IL (US)

(73) Assignee: **Caterpillar Inc.**, Peoria, IL (US)

(**) Term: **15 Years**

(21) Appl. No.: **29/587,757**

(22) Filed: **Dec. 15, 2016**

(51) **LOC (10) Cl.** **15-03**

(52) **U.S. Cl.**

USPC **D15/29; D15/28**

(57) **CLAIM**

The ornamental design for a tip for a ground engaging machine implement, as shown and described.

DESCRIPTION

FIG. 1 is a front perspective view of a tip for a ground engaging machine implement showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Grayscale shading represents contour.
